OIL-BURNING AND CONTROL APPARATUS

William Harvey Payne, Hinsdale, Ill.

Application March 26, 1947, Serial No. 737,217

6 Claims. (Cl. 158—28)

1

Heretofore, oil burners have generally been of either the on and off type, which provided full heat or no heat, or of the high and low type, which provided high or low heat. These have generally been regulated between high heat or low and off, by a temperature responsive means positioned in the chamber which was alternately being heated, or sometimes in the path of the heating medium flowing to said chamber.

With only a small number of available rates for the supply of heat, there was necessarily considerable fluctuation over short periods of time of the temperature of the medium heated by the burner. These were sometimes very objectionable. According to the present invention, a practical means is provided for varying the supply of heat through infinitesimal increments so that it can exactly balance the requirements. In addition, the control is obtained through a temperature responsive device in the path of the heating medium passing from the heated chamber to the burner so that the exact amount of heat is supplied which is required to raise the heating medium to the particular temperature desired.

Efficient burning is maintained in spite of the infinitesimal variations by maintaining approximately a constant proportioning of air and oil, both being delivered by displacement pumps which are driven at the same or proportional speeds. Other proportioning devices may be used, and for some aspects of the invention another fuel, such as gas, may be used.

In spite of the variations in rate of delivery of the oil, the discharge pressure is maintained approximately constant by a discharge valve which is biased toward the closed position during operation. In the preferred form of the invention, the biasing force is magnetic and is automatically discontinued when the burner is shut off so that oil can drain from the burner so as not to be carbonized by remaining in the hot burner. A special storage chamber is provided for storing air pressure which is automatically released to blow the oil out of the burner as the burner is being shut down.

Additional objects and advantages of the invention will be apparent from the description and from the drawings in which:

Figure 1 is a largely diagrammatic view of the form of the apparatus chosen for illustration of the invention, a heating unit being shown in vertical cross-section; and

Fig. 2 is a perspective view showing a battery of three core ovens with the heating unit of Fig. 1 on top thereof.

2

Fig. 3 is a diagrammatic view of a modification.

Although the law requires a full and exact description of at least one form of the invention, such as that which follows, it is, of course, the purpose of a patent to cover the new inventive concept therein no matter how it may later be disguised by variations in form or additions of further improvements; and the appended claims are intended to accomplish this purpose by particularly pointing out the parts, improvements, or combinations in which the inventive concepts are found.

Although the invention is capable of a wide variety of uses, it has been shown in conjunction with a unit heater 11 associated with a core oven 12 having a battery of three oven chambers. The air heated by heater 11 is circulated through the ovens by blower 13. A conduit 14 connects the heater with the blower, conduit 16 connects the blower with the ovens, and conduit 17, one of which is not shown, connects the ovens with the intake chamber of the heater unit 11.

The heater unit

As seen in Fig. 1, the heater unit 11 may include an intake chamber 21, a combustion chamber 22, and a mixing and outlet chamber 23. Air and gases which have given off their heat in the ovens 12 enter the heater through chamber 21, which may be considered part of the return duct, are heated by the flame in combustion chamber 22, and pass through chamber 23. From the chamber 23, the heated gases flow through the blower 13 back to the ovens.

Burner

The burner comprises an outer air flow tube 26 and an inner oil flow tube 27. The tube 27 together with spreader or valve 28 forms a nozzle from which the oil is sprayed into the incoming air. Any suitable means may be combined for starting combustion but thereafter it continues as long as the oil and air are supplied.

Proportional feed

Oil is supplied to the inner tube 27 by a pump 31 which is preferably a gear pump or other type of displacement pump. Air is supplied to the outer tube 26 by a pump 32 which is also preferably a displacement pump, such as a Roots type blower. By a positive displacement pump is meant any pump in which the discharge per revolution is approximately constant, regardless of the pump's speed. Thus, the rate of discharge

is independent of pressure and the rate of discharge per minute is proportional to the speed of the pump. The pumps 31 and 32 are driven at speeds which bear a fixed proportional relation to one another, preferably being driven at the same speed. Thus, they will always feed oil and air at a given volume ratio. In the illustrated form, they are both driven by a motor 33 which is a variable speed, direct current motor of the shunt type.

Control system.

According to one feature of the present invention, the proper quantities of fuel and air are at all times supplied to bring the temperature of the incoming gases up to a predetermined value. The amount of fuel and air required is, in effect, determined by thermocouple 36 located in the air to be re-heated. It will be understood that the volume of gases to be heated is constant, blower 13 being a conventional type without speed variation control. As diagrammatically illustrated in Fig. 1, the thermocouple 36 is connected to an amplifier 37 which, in turn, is connected to a torque motor 38. The torque motor 38 drives a contact arm 39 of a rheostat to vary the amount of resistance 41 connected in the field circuit of the motor. The field coil 42 has been illustrated as a shunt field with the result that its excitation determines the speed at which the motor 33 operates and, hence, the speed at which pumps 31 and 32 operate.

If the temperature of the incoming gases in chamber 21 drops, thermocouple 36 calls for more heat and causes rheostat arm 39 to move to the position which will drive motor 33 and pumps 31 and 32 at the speed which will give the required amount of heat. The resistance 41 can be distributed so that, in effect, it calibrates the torque motor 38 to provide the desired amount of heat for various torque motor indications, to supply the heat deficiencies which they represent. A calibrating effect can also be accomplished by adjustments of the amplifier 37.

To guard against possible excessive heat, an additional heat responsive element 46 may be placed in the stream of heating medium passing from the heater. It may actuate a contact 47 of relay 48 to shunt out resistance 41 when the heat is excessive. This makes the motor 33 run at minimum speed. If desired, the relay 48 could be connected to shunt out only a small and perhaps adjustable part of resistance 41 so that it would merely slightly decrease the speed of motor 33.

The relay 48 may be designed or adjusted to act either with slow reaction as a limit switch to prevent very serious overheating, or with quick reaction to modulate the average speed of the motor when a temperature only slightly above the desired temperature is reached. In the latter case, it will function more frequently, at least if the regulation of pump motor 33 is designed to provide a slight excess of the desired heat so as never to fall materially below the required level. Alternatively, the heat responsive element 46 could be connected to cause the supply of a slight additional increment of heat whenever its temperature falls below a predetermined value. Its use as a limit switch with regulation of the motor 33 by rheostat arm 39 as accurately as may be desired is preferred inasmuch as this will give the most uniform heat.

The entire control and drive apparatus may be powered by any suitable source of direct current. The direct current may be obtained from alter-

nating current supply wires 51 connected to a rectifier diagrammatically indicated at 52.

Oil drainage from burner

In order that the oil be sprayed at substantial pressure in a thin sheet when the volume is low as well as when the volume is high, the spreader or spray plate 28 is preferably mounted and is urged toward the closed position. The biasing means preferably acts with approximately constant force during operation so as to maintain a uniform oil pressure. A varying biasing force could be provided if preferred. It is desirable that the biasing force be discontinued when the burner ceases to operate, so that oil which might otherwise be trapped in the burner can escape. This prevents carbonization of the oil under the influence of the heat of the furnace. One method of biasing the spray plate 28 during operation and leaving it unbiased at other times is by a solenoid 53 which may be connected to the main power wires 54 as shown. The connection may be anywhere in which it is subject to de-energization whenever control switch 56 is operated to shut off the motor 33. In place of the simple solenoid 53 illustrated, a motor could be used (Fig. 3) with the rotor 58 connected to the stem 57 of spray plate 28 so as to rotate this spray plate to cut up slugs of heavy oil or even roll any harder particles so that they can pass through the burner. In this event, the rotor 58 would be axially displaced from the magnetic center of stator 59 so that magnetism of the motor would bias the stem 57 and spray plate 28 in the closing direction. A spring biasing means could alternatively be used with a limit device to prevent the spray plate 28 from quite closing on the burner nozzle.

Discharge of the oil may be ensured by providing means for blowing it out of the burner after shut down of the apparatus. To this end, an air storage tank or chamber 61 may be provided with check valves 62 and 63 arranged as diagrammatically illustrated. During operation of the blower 32, air under pressure is blown into storage chamber 61. Inasmuch as the oil will be under a still higher pressure, this air cannot escape through check valve 63. The check valve itself prevents entrance of oil in the chamber 61. As the apparatus is shut down, the air pressure from blower 32 will decrease but check valve 62 will prevent escape of air through it from the chamber 61. As the oil pressure drops due to stopping of the pump 31, the compressed air in chamber 61 will open check valve 63 and escape through the oil burner conduit 27 blowing from the oil burner conduit 27 the oil which might otherwise carbonize.

To prevent seepage of oil when pump 31 is not operating, a valve 64 is provided. If the oil level is always below the burner, this may be a simple check valve. If the oil level is as high as the burner, the valve 64 is loaded with sufficient biasing force to close in spite of the hydrostatic pressure of the oil, although, of course, opening under the greater pressure resulting from actuation of pump 31.

It will be understood that many variations may be made from the illustrated embodiment now preferred. Although displacement pumps will give the most positive proportioning, other kinds of pumps could be used, at least if the two pumps are of similar type and balanced so that the proportions of air and oil remain constant at different speeds.

Although a variable speed motor has been illus-

trated, a constant speed motor could be provided, the pumps being driven through a variable speed drive capable of infinitesimal change. Likewise, other motor speed regulators could be provided, such as governors or speed regulators responsive centrifugally or otherwise to the speed of the motor. To safeguard against variations in the rheostat 39 or other speed regulating device, a follow-up system can be used in which the position of the regulating device does not vary as a result of variations in the torque value moving it. In that event, the follow-up system may be made responsive to the position of the torque motor 38 or it may be made more directly responsive to the heat responsive element 36.

Although the invention has been disclosed in connection with oil, it is apparent that gas or other fuel could be burned with suitable changes in the mechanism, the control remaining virtually the same. In the case of gas, gas at constant pressure could be pumped by a gas pump or blower in the position of pump 31. Alternatively, a valve could be opened varying amounts correlated with the varying speeds of the air blower 32. With a stoker, the blower and stoker feed could be jointly driven. The stoker feeds are conventionally of a displacement type such as a screw conveyor. By using a blower of the displacement type as previously indicated, the proportions of fuel and air would be approximately constant at the varying speeds.

It will be recognized that instead of the direct heating system illustrated, an indirect system may be used. In that, the burner and combustion chamber are separated from the circulating medium so that the latter is not mixed with the products of combustion.

From the foregoing it is seen that a heating and fuel burning apparatus has been developed in which the amount of heat supplied is exactly the amount required to bring the temperature of the heating medium to a desired value. This has a wide range of possible usefulness, even being adaptable to house heating. It is most advantageous in combination with a modulating type of burner or heat generator. It is also seen that a modulating oil burning apparatus is provided in which the proportions of fuel and air are constant in spite of a wide range of minute variations in their volumes. In the case of an oil burner, the oil is maintained under approximately constant pressure so as to be satisfactorily sprayed from the oil nozzle at different speeds, the spray plate tending to close the nozzle to maintain the pressure but being unbiased when the burner is shut down so that oil can escape and avoid being carbonized. The discharge of the oil from the burner nozzle is ensured by an air storage chamber which delivers air under pressure to the oil conduit in the nozzle after shut down.

I claim:

1. Oil burning apparatus including a burner having an oil conduit and an air conduit, each terminating at a nozzle, a spray plate adjacent the oil nozzle opening, biasing means for urging said nozzle spray plate toward said opening, including an electromagnetic unit energized when said oil burning apparatus is operating, and at other times being de-energized and releasing said spray plate, and blow-out means including a storage chamber, a check-valve connection from the air conduit to the storage chamber to fill the storage chamber with air under pressure, and a check valve connection from the storage

chamber to the oil conduit to blow oil from the nozzle as the pressures reduce in shutting off the apparatus.

5 2. Oil burning apparatus including a burner having an oil conduit and an air conduit, each terminating at a nozzle, a spray plate adjacent the oil nozzle opening, and biasing means for urging said nozzle spray plate toward said opening including an electromagnetic unit energized when said oil burning apparatus is operating, and at other times being de-energized and releasing said spray plate.

15 3. Oil burning apparatus including a burner having an oil conduit and an air conduit, each terminating at a nozzle, means for constricting the discharge of oil to maintain a pressure for throwing a stream, and blow-out means including a storage chamber, a check-valve connection from the air conduit to the storage chamber to fill the storage chamber with air under pressure, and a check valve connection from the storage chamber to the oil conduit to blow oil from the nozzle as the pressures reduce in shutting off the apparatus.

20 4. Oil burning apparatus including a burner having an oil conduit and an air conduit, each terminating at a nozzle, a spray plate adjacent the oil nozzle opening, and biasing means for urging said nozzle spray plate toward said opening including an electromagnetic unit energized when said oil burning apparatus is operating, and at other times being de-energized and releasing said spray plate, means for supplying oil and air to said burner including a displacement type oil pump, a displacement type air pump, and means for driving said pumps with their speed relationship fixed proportionally, but with their speed jointly varied.

25 5. Oil burning apparatus including a burner having an oil conduit and an air conduit, each terminating at a nozzle, a spray plate adjacent the oil nozzle opening, and biasing means for urging said nozzle spray plate toward said opening including an electromagnetic unit energized when said oil burning apparatus is operating, and at other times being de-energized and releasing said spray plate, means for supplying oil and air to said burner including a displacement type oil pump, a displacement type air pump, and means for driving said pumps with their speed relationship fixed proportionally, but with their speed jointly varied, and blow-out means including a storage chamber, a check-valve connection from the air conduit to the storage chamber to fill the storage chamber with air under pressure, and a check-valve connection from the storage chamber to the oil conduit to blow oil from the nozzle as the pressures reduce in shutting off the apparatus.

30 6. Oil burning apparatus including a burner having an oil conduit and an air conduit, each terminating at a nozzle, means for spraying oil and air respectively to said conduits in fixed proportions but at varying rates to modulate the burner, a spray plate adjacent the oil nozzle opening, biasing means for urging said nozzle spray plate toward said opening, including an electromagnetic unit energized when said oil burning apparatus is operating, and at other times being de-energized and releasing said spray plate, and blow-out means including a storage chamber, a check-valve connection from the air conduit to the storage chamber to fill the storage chamber with air under pressure, and a check valve connection from the storage chamber to the

oil conduit to blow oil from the nozzle as the pressures reduce in shutting off the apparatus.
